LIGHT MODULATING CYLINDER

Clyde L. Tichenor, Los Angeles County, Calif., assignor
to Warwick Electronics Inc., Chicago, Ill., a corpora-
tion of Delaware

Filed May 26, 1965, Ser. No. 85,469

Term of patent 14 years

(Cl. D48—16)

FIGURE 1 is a side view in elevation of the light modulating cylinder showing my new design;

FIGURE 2 is a plan view of the light modulating cylinder;

FIGURE 3 is an elevational view of the light modulating cylinder as seen from the rear;

FIGURE 4 is an elevational view of the light modulating cylinder as seen from the bottom; and

FIGURE 5 is a sectional view of the light modulating cylinder.

I claim:

The ornamental design for a light modulating cylinder, substantially as shown.
